UNITED STATES PATENT OFFICE

SANFORD A. MOSS, OF LYNN, MASSACHUSETTS, ASSIGNOR TO GENERAL ELECTRIC COMPANY, A CORPORATION OF NEW YORK

CONTROL MECHANISM FOR SUPERCHARGERS

Application filed January 31, 1927. Serial No. 164,956.

The present invention relates to super-chargers for internal combustion engines, wherein the compressor for supplying air to the engine is driven by a turbine operated by exhaust gas from the engine. A construction embodying my invention is well adapted for use in supercharging the engine of aeroplanes, although it is not limited to this use, but may be used wherever found applicable.

The object of the invention is to provide an improved regulating mechanism for super-chargers of the above-referred-to type, and for a consideration of what I believe to be novel and my invention, attention is directed to the accompanying description and the claims appended thereto.

In the drawings, Fig. 1 is a top plan view, partly in section and partly diagrammatic, of an internal combustion engine provided with a supercharger and regulating mechanism embodying the invention; Fig. 2 is a sectional view through the nozzle box of the turbine, and Fig. 3 is a view, mostly in transverse section, of a gas-driven turbo-compressor set.

Referring to the drawings, 1 indicates an internal combustion engine of any suitable type. In the present instance, a 12-cylinder V-type engine is shown. 2 indicates the cylinders of the engine; 3 indicates the intake manifold, and 4 indicates the exhaust manifold.

Intake manifold 3 is connected by a conduit 5 to the discharge side of a suitable carburetor 6. Carburetor 6 is shown diagrammatically and is indicated as being provided with a pipe 7 through which gasoline is supplied to it from any suitable source. The intake side of carburetor 6 is connected by a conduit 8 to the discharge conduit 9 of a centrifugal compressor 10. 11 indicates the impeller of the compressor. It is carried by shaft 12 mounted in suitable bearings in the compressor casing. On one end of shaft 12 is a turbine wheel 13 to which actuating fluid is supplied by nozzles 14, located in the nozzle box 15. Nozzle box 15 is annular in contour and is divided by partition plates 16 into a plurality of separate chambers. In the pres-

ent instance, three chambers are shown, numbered 17, 18 and 19. Each of these chambers covers a certain arc of the nozzle box, and hence supplies gases to the nozzles 14 in such arc. Chambers 17, 18 and 19 are connected by conduits 20, 21 and 22 to exhaust manifold 4. Connected to conduit 20 is a conduit 23 which communicates directly with the atmosphere. It is provided with a valve 24 by means of which it may be opened and closed. Conduits 21 and 22 are provided with valves 25 and 26, by means of which they may be opened and closed. On the outer ends of the spindles of valves 24, 25 and 26 are arranged disks 27, 28 and 29, each provided with a slot 30 in its edge. Valves 24, 25 and 26 are arranged to be in either fully open or fully closed positions, and when in either of such positions are held by means of suitable springs. In the present instance, disks 27 and 28 are shown as being connected together by a spring 31 connected at its ends to pins 32 on the disks. Each disk is also provided with a stop pin 33, against which the ends of spring 31 strike to limit the movements of the valves toward open positions. Disk 29 is provided with a pin 34 to which is connected one end of the spring 35. The other end of spring 35 is connected to a pin 36 projecting from the wall of conduit 21. On disk 29 is a stop pin 37 for limiting the movement of valve 26 toward open position. The ends of the springs 31 and 35 connected to the respective disks 27, 28 and 29 are adapted to move from one side of the centers of the disks to the other side when the disks are turned to open and close the valves. In the positions shown in Fig. 1, valves 24, 25 and 26 are open, as is shown in Fig. 2. If now disk 27 is turned in an anti-clockwise direction, valve 24 will be moved toward closed position, and as soon as pin 32 moves beyond the center of disk 27, spring 31 will act to move the valve quickly to its fully closed position, the valve engaging the inner surface of conduit 23 to limit the movement of the valve. Similar actions take place when disks 28 and 29 are turned in an anti-clockwise direction. For actuating the valves 24, 25 and 26 there is

teeth 39 adapted to engage with the notches 30. Teeth 39 are positioned so that when rod 38 is moved toward the left as viewed in Fig. 1, the disks 27, 28 and 29 will be engaged one after the other, the arrangement being such that as the rod is moved toward the left, valve 24 will be closed, then valve 25 will be closed, and finally valve 26 will be closed. Upon movement of rod 38 in reverse direction, after 10 the valves have been closed, valve 26 will be opened first, after which valve 25 and valve 24 will be opened successively.

The right-hand end of rod 38 is connected to a piston 40 located in a cylinder 41. Associated with cylinder 41 is a pilot valve structure 42 which controls admission of actuating fluid to the cylinder on opposite sides of piston 40. Actuating fluid is supplied to the pilot valve by a pipe 43 which is connected 20 to exhaust manifold 4. This forms a usual type of pilot valve controlled fluid-actuated motor, the operation of which is well understood. The stem of pilot valve 42 is connected to the central portion of a lever 44. 25 One end of lever 44 is connected to rod 38 and the other end is connected to the central portion of a floating lever 45. The upper end of lever 45 is connected by a link 46, a lever 47 which is pivoted at 48, and a link 49 30 to a hand lever 50 which is adapted to be positioned along an arcuate segment 51. The lower end of floating lever 45 is connected by a stem 52 to the movable end of a bellows 53 located in a sealed casing 54, the non-movable end of the bellows being fixed 35 directly to the base 55 of casing 54.

The interior of bellows 53 has the air removed from it so that there is a vacuum in it. Casing 54 is connected by a pipe 56 to 40 intake manifold 3, which means that bellows 53 is subjected on its outer surface to the pressure in the intake manifold. Surrounding stem 52 is a spring 57 located between the top wall of casing 54 and an adjustable nut 45 58 threaded on stem 52. The collapsing of bellows 53 by the pressure to which it is subjected in casing 54 is thus opposed by spring 57.

The operation is as follows: When the 50 aeroplane is on the ground, no supercharging being then desired, piston 40 stands in the position shown in Fig. 1, and valves 24, 25 and 26 are wide open. The pressure in intake manifold 3 is substantially atmospheric pressure and the arrangement is such that bellows 53 being subjected to atmospheric pressure is collapsed against the action of spring 57 to an extent such as to maintain the pilot valve closed when piston 40 is in the position 55 shown. With the engine running, the exhaust gases have two avenues for escape, one through conduit 23 directly to atmosphere and the other through the nozzles 14 and the buckets of turbine wheel 13 directly to atmosphere. Under these conditions the pres-

sure in the exhaust manifold will be substantially atmospheric pressure. As a result, therefore, there will be a drop in pressure between the admission and exhaust sides of the nozzles 14 so small that little if any exhaust gases will pass through the nozzles. Such gases as do escape through the nozzles may serve to keep the turbine wheel turning very slowly, but not at a speed such as would produce an appreciable amount of super-charging.

If now the aeroplane rises in the air and reaches an altitude of a certain lower pressure, then the pressure in casing 54 will decrease, whereupon bellows 53, due to its inherent elasticity coupled with the action of spring 57, will effect a movement of the lower end of floating lever 45 toward the right. At this time, the upper end of lever 45 is held stationary by link 46 so that lever 45 turns on the end of link 46 as a pivot. This moves the lower end of lever 44 toward the right, thus moving pilot valve 42 toward the right. Fluid under pressure from pipe 43 then flows through the right-hand passage of the pilot valve to the right-hand side of piston 40, moving piston 40 toward the left and effecting the closing of valve 24. As piston 40 moves toward the left, the upper end of link 44 which is connected to rod 38 moves with it, the same pivoting about its connection with floating lever 45. This serves to restore the pilot valve to its former position. When valve 24 closes, the escape of exhaust gases to the atmosphere is cut off so that now the only avenue of escape for them is through the nozzles 14. At this time all three chambers, 17, 18 and 19, are connected to the exhaust manifold so that the exhaust gases are fed to the entire ring of nozzles 14. There will be now a certain drop in pressure across nozzles 14 sufficient to effect the discharge of the exhaust gases through them. This will serve to build up a certain back pressure on the engine and effect operation of the turbine wheel at a certain speed. The arrangement is such that when all the nozzles 14 are available for the passage of exhaust gas, a back pressure of but small 100 value will be built up on the turbine. As a result, the turbine will be operated at a comparatively slow speed and will produce only a predetermined amount of supercharging.

Due to the operation of impeller 11 at a higher speed, the pressure in intake manifold 3 will be increased. This increased pressure will act on bellows 53, tending to collapse it again, which, of course, tends to operate piston 40 in a direction opposite to that just described. However, the arrangement is such that the parts will come to a stable position with valve 24 closed when a certain predetermined pressure is reestablished on casing 54. This pressure will be substantially that which existed previously in casing 54, al-

though it will be slightly less, due to the inherent width of regulation of the governing mechanism.

If now the pressure in the intake manifold again decreases, then the operation just described will be repeated, piston 40 being moved so as to effect closing of valve 25. When valve 25 closes, the nozzle area supplied with gases from the chamber 18 is shut off so that all the exhaust gas must escape through the nozzles fed by chambers 17 and 19. Due to the more limited nozzle area available for the passage of the exhaust gases, the back pressure on the turbine will 15 be further built up, whereupon there will be effected a greater drop in pressure across the nozzles now in action which will serve to increase further the speed of the supercharger. Compressor 11 will thereupon operate to increase the pressure of the air supplied to the carburetor.

If now another decrease in pressure in intake manifold 3 occurs, then the mechanism will be operated after the manner already 25 described, to effect closing of valve 26. This then shuts off the supply of exhaust gases to the nozzles of chamber 19 so that all the exhaust gases from the engine must pass through the nozzles fed from chamber 17. As a result the back pressure on the turbine 30 will be built up still further, which means that there will be a greater drop in pressure across nozzles 14, thereby further increasing the speed of the turbine wheel and hence 35 the amount of supercharging.

Thus it will be seen the supercharger will be increased automatically from zero to its maximum value.

If the supercharging pressure increases 40 beyond the desired value, then bellows 53 is collapsed, operating piston 40 in the opposite direction to that just described, whereby there is effected opening movement of the valves 26, 25 and 24 in the reverse order to 45 their closing movements.

By means of hand lever 50 the floating lever 45 can be moved to effect adjustment of the supercharger at any time or to set it for any desired pressure. The automatic mechanism comprising bellows 53 then serves to 50 maintain such pressure automatically.

While I have shown only one atmospheric valve 24 and two nozzle controlling valves 25 and 26, it will be understood that the number may be varied as found desirable; also, it will be understood that the valves may be operated in any suitable manner. Preferably, I operate the valves from wide open to completely closed position, as this avoids 55 throttling. However, it is to be understood that the valves may be operated in any other suitable manner, if desired.

In accordance with the provisions of the patent statutes, I have described the principle of operation of my invention, together

with the apparatus which I now consider to represent the best embodiment thereof, but I desire to have it understood that the apparatus shown is only illustrative and that the invention may be carried out by other means.

What I claim as new, and desire to secure by Letters Patent of the United States, is:

1. The combination with an internal combustion engine, of a supercharger comprising a turbine, conduit means for conveying exhaust gases from the engine to the turbine, conduit means for conveying exhaust gases from the engine directly to atmosphere, and means for successively shutting off the second named conduit means and then diminishing the passage area through the turbine to effect increase in the amount of energy imparted by the gases to the turbine.

2. The combination with an internal combustion engine, of a supercharger comprising a turbine, conduit means for conveying exhaust gases from the engine to the turbine, conduit means for conveying exhaust gases from the engine directly to atmosphere, and automatic means controlled by the supercharger pressure for successively shutting off the second named conduit means and then diminishing the passage area through the turbine to effect increase in the amount of energy imparted by the gases to the turbine.

3. The combination with an internal combustion engine, of a supercharger comprising a turbine, nozzles for the turbine, conduit means for conveying exhaust gases from the engine to the nozzles, conduit means for conveying exhaust gases directly to atmosphere, said nozzles having a total area such that when both said exhaust conduit means are open but little energy will be expended on the turbine rotor, and means for successively shutting off the second named conduit means and then diminishing the nozzle area available for gas flow to thereby increase the amount of energy expended on the turbine rotor.

4. The combination with an internal combustion engine, of a supercharger comprising a turbine, nozzles for the turbine, conduit means for conveying exhaust gases from the engine to the nozzles, conduit means for conveying exhaust gases directly to atmosphere, said nozzles having a total area such that when both said exhaust conduit means are open but little energy will be expended on the turbine rotor, and automatic means actuated by the supercharger pressure for successively shutting off the second named conduit means and then diminishing the nozzle area available for gas flow to thereby increase the amount of energy expended on the turbine rotor.

5. The combination with an internal combustion engine, of a supercharger comprising a turbine, groups of nozzles for the tur-

bine, conduit means for conveying exhaust gases from the engine to said groups of nozzles, conduit means for conveying exhaust gases from the engine directly to atmosphere, and valve means for successively closing said last named conduit means and then cutting groups of nozzles out of action to effect a building up of the back pressure on the engine to increase the drop in pressure through the 10 nozzles.

6. The combination with an internal combustion engine, of a supercharged comprising a turbine, groups of nozzles for the turbine, conduit means for conveying exhaust gases from the engine to said groups of nozzles, conduit means for conveying exhaust gases from the engine directly to atmosphere, and valve means controlled automatically by the supercharger pressure for successively closing said last named conduit means and then cutting groups of nozzles out of action to effect a building up of the back pressure on the engine to increase the drop in pressure through the nozzles. 15

20 7. The combination with an internal combustion engine, of a supercharger comprising a turbine, conduit means for conveying exhaust gases from the engine to the turbine, conduit means for conveying exhaust gases from the engine directly to atmosphere, automatic means controlled by the supercharger pressure for successively shutting off the second-named conduit and then diminishing the 25 passage area through the turbine to effect increase in the amount of energy imparted by the gases to the turbine, and manually-operated means for effecting adjustment of the supercharger pressure. 30

35 8. The combination with an internal combustion engine, of a supercharger comprising a turbine, nozzles for the turbine, conduit means for conveying exhaust gases from the engine to the nozzles, conduit means for conveying exhaust gases directly to atmosphere, said nozzles having a total area such that when both said exhaust conduit means are open but little energy will be expended on the turbine rotor, automatic means actuated by the supercharger pressure for successively 40 shutting off the second named conduit means and then diminishing the nozzle area available for gas flow to thereby increase the amount of energy expended on the turbine 45 rotor, and manually-operated means for effecting adjustments of the supercharger pressure. 50

55 9. The combination with an internal combustion engine, of a supercharger comprising a turbine, groups of nozzles for the turbine, conduit means for conveying exhaust gases from the engine to said groups of nozzles, conduit means for conveying exhaust gases from the engine directly to atmosphere, valve means controlled automatically by the super- 60 charger pressure for successively closing said 65

70 last named conduit means and then cutting groups of nozzles out of action to effect a building up of the back pressure on the engine to increase the drop in pressure through the nozzles, and manually-operated means for effecting adjustment of the supercharger pressure.

75 In witness whereof, I have hereunto set my hand this 28th day of January, 1927.
